UNITED STATES PATENT OFFICE

DWIGHT L. BEATTY, OF MISSOULA, MONTANA

GRADING AND DITCHING MACHINE

Application filed October 5, 1927. Serial No. 224,260.

This invention relates to earth working machines, particularly to graders and ditchers, and has for its object the provision of a novel machine or device for constructing and maintaining trails, ditches, fire-lines, roads and the like, in a convenient and inexpensive manner.

An important object of the invention is to provide a machine of this character which is adapted to work as effectively under difficult conditions, such as where roots, rocks and the like abound, as under other conditions where no such difficulties exist.

Another object of the invention is to provide a machine of this character which is reversible so that material may be graded or scraped away either to the right or to the left, depending upon the slope where it is desired to build a trail road, ditch, fire-line or the like.

Another object of the invention is to provide a machine of this character which may be easily disassembled and packed for transportation, especially on the back of a horse, mule or other pack animal, it being highly desirable that the machine be readily portable so as to be well adapted for employment in the forestry service or in other branches of industry, where it is necessary to make quick jumps in rough country.

A still further object is to provide a device of this character provided with adjustable means whereby the depth of cut may be regulated depending upon the nature of the soil worked upon, the number of roots, rocks or other obstructions to be encountered, or other conditions which may exist.

Yet another object is to provide a grading machine of this type which is provided with handle means whereby it may be manually controlled or steered by an operator walking behind it, the device being drawn along by a draft animal, tractor or the like, depending upon circumstances, or the device being actually pushed by the workman, these various details being considered immaterial.

An additional object is to provide a machine of this character which will be comparatively simple and inexpensive in manufacture, easy to assemble and adjust, positive

in action, efficient and durable in service, and a general improvement in the art.

With the above and other objects and advantages in view, the invention preferably consists in the details of construction and the arrangement and combination of parts to be hereinafter more fully described, and claimed, and illustrated in the accompanying drawings, in which:

Figure 1 is a side elevation of the machine. 60

Figure 2 is a top plan view.

Figure 3 is a plan view with the machine turned over so as to grade or move the excavated or scraped earth in the opposite direction. 65

Figure 4 is a vertical cross sectional view taken on the line 4-4 of Figure 2.

Figure 5 is a detail longitudinal section taken substantially on the line 5-5 of Figure 2. 70

Figure 6 is a vertical cross sectional view taken on the line 6-6 of Figure 2.

Figure 7 is an inside elevation of one of the main members of the machine.

Figure 8 is a similar view looking at the 75 inside of the other main member or mold board.

Figure 9 is a perspective view of one of the pivotally connected supporting members.

Figure 10 is a similar view of the other of 80 said members.

Figure 11 is a fragmentary side elevation showing the scraping members in place, and Figure 12 is a fragmentary plan view.

Referring more particularly to the drawings, I have shown the device as comprising a land side and a mold board designated respectively and generally by the numerals 1 and 2, these elements being pivotally and adjustably connected and provided with handle means to be described. The land side 1 comprises an elongated plane or flat steel plate 3 which is preferably rectangular in shape and which has suitably secured upon its inner side at substantially its longitudinal center a reinforcing member 4 here disclosed as a T-beam. Also secured upon the inner face of the plate 3 are upper and lower bracket members 5 of angular formation and preferably constructed as castings, each 100

bracket member having sockets 6 and 7 there-
in for a purpose to be described. Suitably
secured upon the forward end of the plate 3,
as for instance by means of bolts 8 is a plate
member 9 formed at its rear edge with verti-
cally alined apertured ears 10 and also pro-
vided at its rear corners with key-hole slots
11.

The mold board 2 is shown as comprising
10 a main central plate member 12 which is
serpentine in cross section and of such form
that its central and edge portions are
concave-convex in cross section. Riveted or
otherwise suitably secured to the upper and
15 lower edge portions of this member 12 are
blades 13 which, together with the member
12 are preferably so formed at their forward
ends as to be of crescent shape or concaved
as clearly indicated in Figure 1. Clearly, in
20 case of wear, the blades 13 may be removed
and replaced by the new ones or may be
simply taken off and sharpened or, possibly,
sharpened without being removed from the
machine. Suitably secured to the forward
25 end portion of the member 12 is a hinge
member 14 having lugs 15 thereon from
which rise pintles 16 engaged within the
apertured ears 10. If desired, the aperture
in one ear 10 may be of key-hole shape and
30 the lower pintle member 16 may have a key-
shaped head 17 thereon, the arrangement
being such that in a certain position of the
members 9 and 14, withdrawal of the pintles
16 may be effected whereas in other positions,
35 such withdrawal would be impossible. By
means of this particular connection it will
be observed that the mold board is pivoted
for lateral movement with respect to the land
side and is capable of being readily detached
40 therefrom whenever it is desired to disassem-
ble the machine.

At its forward end the land side member
1 is provided with a removable cutter point
or blade 18 which is of course sharpened so
45 as to facilitate its passage through the ground
and to enable it to cut through roots or the
like which may obstruct passage of the
machine along its path. Instead of employing
this cutter as disclosed in Figures 1, 2 and 3,
50 I may provide a share indicated at 19 in Fig-
ures 11 and 12, this share including a main
or body portion 20 and laterally extending
wings 21 at its upper and lower ends, the
wings being preferably braced by the ele-
55 ments indicated at 22. It is of course clear
that the construction of this share or point
must be such that it may be readily removed
for sharpening purposes or for replacement
when it becomes broken or excessively worn.
60 Suitably secured upon the inner side of the
mold board 2 are angular brackets 23 with
which are pivotally connected, at 24, the ends
of bars 25 which converge and which have
their other ends engaged upon opposite sides
65 of the horizontal web or rib of the angle bar

4, a pivot bolt 26 passing through the ends of
these arms and through the rib or web as
thoroughly indicated in Figure 4. The bars
25 are shown as held in the proper relation
70 by means of a spacing sleeve 27 disposed be-
tween them and containing a bolt 28 which
passes through the arms or bars 25 as clearly
indicated in Figure 4. The horizontal flange
75 or web of the angle bar 4 is shown as provided
with a series of holes 29 through a selected
one of which may be inserted a bolt or pin
26 depending upon the desired angular pos-
ition of the mold board with respect to the
land side.

An additional means for maintaining the
mold board in its proper relation to the land
side is shown as comprising a bar 30 having
one end provided with an angular head 31
engaged through a key-hole slot 32 in the
80 plate 3 and through the proper one of the
key-hole slots 11 in the member 9. Attention
is directed to the fact that the key-hole
slots 32 and 11 register and are provided near
both edges of the plate 3 and member 9 for
85 a reason to be described. Pivots connected
with the bar 30, as by a pin or the like 33
is a clevis 34 provided on one end with a
curved arm 35 which arches up over the mold
board and which has its other or free end re-
90 movably engaged within a socket member 36.
The bar 30 is represented as provided
throughout its length with a plurality of
holes 37 within a selected one of which may
be engaged the pivot pin or bolt 33 for adjust-
95 ing purposes. Any suitable draft device, not
shown, may be attached to the arm 30 so that
the device may be drawn along the ground
though it is conceivable that a hitch of suit-
able character may be provided at any other
100 desired point.

In order that the device may be properly
steered as it is drawn along, I provide a pair
of handles 38 and 39, the former being located
preferably in the same plane as the land side
1 and the latter being arranged at an angle
thereto as clearly indicated in Figure 2. The
handle members 38 and 39 have shank por-
tions 40 and 41 respectively engaged within
the sockets 6 and 7 respectively.

In order that the height of the rear end of
the device may be regulated so as to control
the depth to which the front end will cut or
bite, I provide control means or adjusting
means here shown as comprising plates 42
pivoted at 43 upon the rear portion of the
land side and adapted to be held at a selected
position by means of bolts 44 passing through
suitable holes in the land side and through
a selected one of a series of holes 45 in the
115 plates 42. Clearly, these plates may be ad-
justed so as to vary the height of the rear end
of the machine with respect to the ground
traveled over. Attention is directed to the
fact that the machine is the same at the top
120

and bottom so that it may be arranged as in Figure 2 to throw the dirt in one direction or inverted and arranged as in Figure 3 for throwing the dirt in the other direction, the only change necessary in the arrangement of parts to effect this reversal being that the handle members must be removed from their sockets and reengaged therein from the opposite side and that the arm 35 and bar 30 must be changed from one side to the other in a manner which will be readily apparent owing to the provision of the two sets of key-hole slots 32 and lugs.

In the operation of the machine, it will of course be apparent that when it is drawn along the ground by horse power, tractor power or simply pushed by an operator, the blade at the forward end thereof will operate to dig or cut into the soil and through roots or the like. Furthermore, this blade will act to dislodge stones or rocks or any other obstructions so that as the machine is moved along the mold board 2 will act to throw this loosened material to one side or the other, depending upon the position of the machine and the slope of the ground in case the machine is used upon a hill side.

From the foregoing description and a study of the drawings, it will be apparent that I have thus provided a simply constructed, inexpensive and easily operated machine for cutting trails, ditches and the like upon level or sloping ground and for forming fire lines, a device embodying all the necessary features of adjustment, and being, moreover, so constructed and arranged as to be readily disassembled for transportation upon the back of a pack animal or the like. It is really believed that the construction, operation and advantages will be readily apparent to one skilled in the art without further explanation.

While I have shown and described the preferred embodiment of the invention, it should of course be understood that I reserve the right to make all such changes in the details of construction and the arrangement and combination of parts as will not depart from the spirit of the invention or the scope of the subjoined claims.

Having thus described the invention, I claim:—

1. In a machine of the character described, a land side including an elongated plate member having a removable cutter thereon, a mold board pivotally connected with the land side, socket members carried by the land side, handles having shank portions removably engaged within said sockets from either side thereof, the mold board and land side being invertible together, a laterally extending apertured bar member carried by the land side and detachably connected therewith, and an arm detachably and pivotally connected with said apertured bar member and detachably connected with the mold board, said arm

being arched and disposable to extend over the mold board at either edge thereof.

2. In a machine of the character described, a land side, a mold board angularly adjustably connected therewith, and a handle structure comprising a single bracket member secured to the inner face of the land side and formed with sockets arranged in angular relation, and handle members having shanks detachably engaged within said sockets from either side thereof and diverging rearwardly.

In testimony whereof I affix my signature.

DWIGHT L. BEATTY.
